US00D586854S

(12) **United States Design Patent**
Tan

(10) **Patent No.:** **US D586,854 S**
(45) **Date of Patent:** **** Feb. 17, 2009**

(54) **PEN**

(75) Inventor: **Junlin Tan**, Ningbo (CN)

(73) Assignee: **Beifa Group Co., Ltd.**, Ningbo (CN)

(**) Term: **14 Years**

(21) Appl. No.: **29/296,693**

(22) Filed: **Oct. 25, 2007**

(30) **Foreign Application Priority Data**

Apr. 27, 2007 (CN) 2007 3 0146773

(51) **LOC (9) Cl.** **19-06**

(52) **U.S. Cl.** **D19/49**

(58) **Field of Classification Search** ..... D19/35, D19/36, 41, 42, 44, 45, 46, 43, 47, 48, 49, D19/50, 51, 54, 55, 56, 57; 24/11 R, 11 F, 24/11 P; 401/55, 99, 100, 104, 105, 106, 401/107, 109, 196, 197, 202, 208, 209, 213, 401/192, 195, 243, 244, 245, 246, 247; 708/107

See application file for complete search history.

(57) **CLAIM**

The ornamental design for a pen, as shown and described.

DESCRIPTION

FIG. 1 is an upper front right perspective view of a pen showing my new design;

FIG. 2 is an exploded lower rear left side perspective view thereof;

FIG. 3 is a right side elevation view of the pen shown in FIG. 1, with the cap removed and placed on the opposite end of the pen;

FIG. 4 is a top plan view of the pen shown in FIG. 1;

FIG. 5 is a bottom plan view thereof;

FIG. 6 is a left side elevation view thereof;

FIG. 7 is a front elevation view thereof;

FIG. 8 is a right side elevation view thereof; and,

FIG. 9 is a rear elevation view thereof.

1 Claim, 4 Drawing Sheets
